UNITED STATES PATENT OFFICE

2,416,362

LIQUID BOMB

Brooks Walker, Piedmont, Calif.

Application May 17, 1943, Serial No. 487,294

5 Claims. (Cl. 102—57)

(Granted under the act of March 3, 1883, as amended April 30, 1928; 370 O. G. 757)

1

The invention described herein may be manufactured and used by or for the Government for governmental purposes without the payment to me of any royalty thereon.

This invention pertains to construction of a bomb for carrying two liquids to be mixed in the flight of the bomb and ready for explosion or bursting on arrival at the target. Other features are the elimination of stuffing boxes leading into the liquid chambers and the elimination of mechanical mixing devices coming into the liquid chambers from the exterior thereof.

Other means are to provide means for keeping the liquids separate until the initial contact of the bomb and then to effect prompt mixing and time delay operation.

The mixing is accomplished by gas pressure from an explosion or from the puncturing of a charged gas cylinder which forces the liquid from one chamber into the other chamber and gives agitated mixing prior to detonation. The seals are broken by pressure to permit the mixing and are safe against leaking during storage.

Other features of the invention will be more particularly pointed out in the attached specification, claims, and drawings in which:

Fig. 1 is a side elevation partly in section of one form of my invention.

Fig. 2 is a partial side view of the upper portion of a bomb mechanism employing another form of my invention.

Fig. 3 is a partial view of the upper section of the bomb mechanism shown in Fig. 1 prior to operation.

Fig. 4 is a cross vertical section through 4—4 of Fig. 1.

Fig. 5 is a cross vertical section through 5—5 of Fig. 1, and

Figure 6 is a fragmentary detail sectional view of the upper portion of the firing pin housing, shown in normal position the means for holding the firing pin inoperative until impact of the bomb.

In all figures like numerals of reference refer to corresponding parts of the various views.

In Figs. 1, 3, 4 and 5, I have shown a bomb having a case 10 a relief valve 12 located in the side thereof and a tail fin assembly 11. The bomb is filled with two liquids in the cavities 40 and 50 which separately are safe against explosion but, when mixed, form a powerful explosive such as nitro tetra oxide. Benzine or gasoline or other hydrocarbons in association with an oxide of nitrogen, the same being generally known as "anilite" explosives, may be employed, or any other

combination of liquids forming an explosive or toxic substance when mixed.

The mechanism for performing the mixing operation is as follows:

5 A propeller 20 is retained in the bomb rack by the usual arming wire 51 usually carrying some clips 52 to prevent accidental withdrawal in handling. When dropped, this wire is withdrawn and the air stream rotates the propeller 20 to unscrew the stem 21 from the firing pin 23 in housing 23'. The spring 22 forces the firing pin 23 against the primer of the blank cartridge 24 which forces plunger 26 down against the pressure chamber 35 to puncture the diaphragm on 10 the lower end thereof by the sharp hollow needle 28. The pressure cylinder is in a container 16. The plunger 26 acts as a valve to prevent escape of the gas after the cylinder is punctured. The gas pressure breaks the seal 29 in the needle 28 and allows the gas to enter the cavity where liquid 40 is stored. This pressure bursts the seals 15a in the lower diaphragm 15b of the container 15. The gas pressure forces the liquid 40 out through these ports 15a to mix with the liquid 50 in the outer chamber. After the liquid 40 has been forced out of its container into mixture with liquid 50 an agitation of the two liquids is continued for a short time by the gas from the inner chamber bubbling up through the mixed liquids.

30 On impact with the bombs the base detonating fuse which is armed by the forcing down of the pressure chamber 35 acts to detonate the mixed liquids. Excessive pressure is released through the pressure relief valve 12. Details of the base detonating fuse are not shown as many types are known that can be armed by the motion of a control rod 38. Fig. 3 shows this construction in its position prior to dropping.

35 Fig. 2 shows a delayed action tail assembly. The propeller 20 unscrews screw 21 from firing pin 23 but does not release it due to the shear pin 47 that passes through the firing pin and wall of a tubular extension on the underside of the top of the housing 23' and retains the firing pin until the jar of impact with a target when the firing pin acts and mixing of the liquids follows as described in connection with Figs. 1 and 3. The base fuse in this case is a time delay fuse 40 actuated by the action of the pressure cylinder 35 through a control rod 38. The time fuse functions after the mixing takes place to perform for ship bombing with the required time delay or for demolition.

50 When a bomb of this type goes through a

multi-floor building, the wiping off of the tail fins does not adversely affect the delayed mixing and delayed functioning of the device as is true of some of the prior art structures using two liquids.

Where I have shown a preferred form of my invention many modifications will be evident and all uses as pointed out here and in the attached claims are a part of this invention.

I claim:

1. In a bomb, a hollow body containing a liquid component of an explosive, a normally sealed container in said body containing another explosive component which in union with the first forms an explosive compound, a pressure chamber in the component container normally in gas tight relation to the contents of the container, a gas filled movable container in said chamber, a frangible seal for said gas container, a hollow puncturing pin having a rupturable seal therein and positioned to puncture said frangible seal upon the axial movement of the gas container to establish communication between the gas container, the pressure chamber and the component container, fracturable means on the component container and rupturable by the pressure of the contents of the component container, and means operable during the flight of the bomb to move the gas container relative to the puncturing pin to puncture the frangible disc.

2. The invention of claim 1 characterized in that the means operable during the flight of the bomb to move the gas container relative to the puncturing pin comprises a plunger mounted in a bore in the top of the pressure chamber and having a portion adapted to engage the gas filled container, a blank cartridge in the bore positioned to move the plunger upon detonation of the cartridge, a spring restrained firing pin arranged to contact the cartridge, and propeller means adapted to release the firing pin during the flight of the bomb.

3. The invention of claim 1 characterized in that the explosive component contained in the normally sealed container, is gaseous.

4. The invention of claim 1 characterized in that the fracturable means on the component container is located at the end of the component container opposite the pressure chamber.

5. In a bomb, a hollow body containing a liquid component of an explosive, a normally sealed container in said body containing another explosive component which in union with the first, forms an explosive compound, a pressure chamber in the normally sealed container in gas tight relation to the contents of said container, a gas filled container in the pressure chamber, means for placing the hollow body, sealed container, pressure chamber, and gas filled container in communication, a closure for the pressure chamber having a bore therein, a plunger slidably in said bore and having a part adapted to contact the gas filled container, a cartridge in the bore adapted, upon detonation, to give impulse to the plunger, a spring restrained firing pin, dual means for locking said firing pin in inoperative position, and a device operative during flight to render one of said means inoperative, the other of said means being operable upon impact to release the firing pin.
